(57) CLAIM

The ornamental design for a cabinet for audiovisual equipment as shown and described.

DESCRIPTION

FIG. 1 is a perspective front view of a cabinet for audiovisual equipment showing our new design;

FIG. 2 is a perspective rear view thereof;

FIG. 3 is a perspective front view in another in-use position thereof;

FIG. 4 is a front view thereof;

FIG. 5 is a rear view thereof;

FIG. 6 is a top plan view thereof;

FIG. 7 is a bottom view thereof;

FIG. 8 is a left side view thereof;

FIG. 9 is a right side view thereof;

FIG. 10 is a perspective front view of a cabinet for audiovisual equipment showing our new design;

FIG. 11 is a perspective rear view thereof;

FIG. 12 is a perspective front view in another in-use position thereof;

FIG. 13 is a front view thereof;

FIG. 14 is a rear view thereof;

FIG. 15 is a top plan view thereof;

FIG. 16 is a bottom view thereof;

FIG. 17 is a left side view thereof; and,

FIG. 18 is a right side view thereof.

The broken lines depicting the remainder of the cabinet for audiovisual equipment forms no part of the claimed design.

1 Claim, 18 Drawing Sheets
